(57) **CLAIM**

We claim the ornamental design for a shoe care machine, as shown and described.

DESCRIPTION

FIG. 1 is a front perspective view of a shoe care machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 2;

FIG. 9 is an exploded front perspective view thereof with the shoe hanger feature separated from the shoe care machine; FIG. 10 is an enlarged front perspective view of the shoe hanger feature shown separately from the shoe care machine, for clarity of illustration; and,

FIG. 11 is a bottom perspective view thereof.

The broken lines in the figures depict portions of the shoe care machine which form no part of the claimed design.

The dot-dash broken lines encircling portions of the claimed design that are illustrated in enlargements form no part of the claimed design.
